CLAIM

The ornamental design for a razor cartridge, as shown and described.

DESCRIPTION

FIG. 1 is a front perspective view of a razor cartridge showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is an enlarged view of the encircled portion in FIG. 1.

The evenly-dashed broken lines in the figures depict portions of the razor cartridge that form no part of the claimed design.

The dot-dash broken lines illustrate the boundary for the enlarged view and form no part of the claimed design.
